DESIGN FOR A STAIR TREAD

William S. Pattison, Johnson County, Kans.

Application January 15, 1938, Serial No. 74,322

Term of patent 14 years

To all whom it may concern:

Be it known that I, William S. Pattison, a citizen of the United States and resident of the county of Johnson and State of Kansas, have invented a new, original, and ornamental Design for a Stair Tread, of which the following is a specification, reference being had to the accompanying drawing, forming part thereof, in which the figure is a perspective view of a stair tread, showing my new design.

I claim:

The ornamental design for a stair tread, as shown.

WILLIAM S. PATTISON.
